[57] CLAIM

The ornamental design for a race car mailbox, as shown and described.

DESCRIPTION

FIG. 1 is a perspective view showing race car mailbox of our new design.

FIG. 2 is a front elevational view thereof.

FIG. 3 is a top plan view thereof.

FIG. 4 is a left side elevation thereof.

FIG. 5 is a right side elevation thereof; and, FIG. 6 is a rear elevation thereof.

The bottom of the mailbox is plain and unadorned. The features illustrated in ghost line do not form a part of the claimed design.
